UNITED STATES PATENT OFFICE.

GEORGE P. WIGGINTON, OF KALAMAZOO, MICHIGAN, ASSIGNOR TO KALAMAZOO LOOSE LEAF BINDER COMPANY, OF KALAMAZOO, MICHIGAN.

LOOSE-SHEET DEVICE.

Application filed January 2, 1925. Serial No. 164.

To all whom it may concern:

Be it known that I, GEORGE P. WIGGINTON, a citizen of the United States, residing at the city and county of Kalamazoo, State of Michigan, have invented certain new and useful Improvements in Loose-Sheet Devices, of which the following is a specification.

This invention relates to improvements in loose sheet devices.

My improvements are especially designed for the handling of loose sheets in accounting or record systems.

The main object of my invention is to provide an improved loose sheet device which enables the rapid and efficient handling and manipulation of loose sheets in making entries and also provides means for securely holding them for filing or reference purposes.

Objects pertaining to details and economies of construction and operation will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this application, in which:

Fig. I is a perspective view of a binder which I preferably employ.

Fig. II is a perspective view of the sheet body bound together as a unit by the post bars removed from the binder.

Fig. III is a side view of the sheet support with the sheet body and post bars arranged in one of the holders, the position of the sheets when arranged in the holder being indicated by dotted lines.

Fig. IV is a plan view with the parts arranged as in Fig. III.

Fig. V is an enlarged detail partially in section on a line corresponding to line 5-5 of Fig. IV.

Fig. VI is a perspective view of the post bars removed from the binder and sheets.

Fig. VII is a detail section on a line corresponding to line 7-7 of Fig. I showing details of the binder.

Fig. VIII is a plan view of one of the sheets.

In the drawing the sectional views are

taken looking in the direction of the little arrows at the ends of the section lines and similar numerals of reference indicate similar parts throughout the several views.

Referring to the drawing, the sheets 1 are provided with notches 2 in their binding edges and holes 3 adjacent their binding edges. I provide a binder which in the structure illustrated comprises a pair of covers 4 having clamping bars 5 hinged thereto, the clamping bars having sockets 6 therein. The binding bars are adjustably connected by means of the flexible strips 7, the notches 2 being positioned to receive these binding strips when the sheets are arranged within the binder.

I provide a pair of post bars 8 which are removably engaged with the clamping bars, the post bars having pins 9 adapted to engage the sockets 6 thereby retaining the post bars within the binder when the clamping bars are clamped upon the sheet body with the post bars engaged therewith. These post bars are provided with posts 10, the posts being of the sectional type so that the binder can be readily adjusted to the sheet body. These post bars have notches 11 aligned with the notches 2 to receive the binding strips 7.

By thus detachably engaging the post bars with the binder the sheet body may be removed from the binder as a unit.

To facilitate the manipulation of the sheets in accounting or machine bookkeeping, I provide a support designated generally by the numeral 12, comprising a pair of V-shaped holders 13 and 14, the holder 13 comprising a side member 15 and the end member 16 and the holder 14 comprising the side member 17 and the end member 18. These side and end members are arranged so that the sheet may be disposed upon the side members of the holders with their ends abutting the end members of the holders.

The side and end members of the holder 13 are arranged at an acute angle relative to each other so that when the sheets are arranged in the holder the upper edges of the sheets are supported in a stepped or "fanned" relation as indicated by dotted lines in Fig. III.

The side and end members of the holder 14 are arranged at right angles to each other so that when the sheets are arranged in this holder with their ends abutting the end

member 18, the ends of the sheets are squared up or brought into the same plane.

These holders are adapted to receive the sheets as a body while bound or held together by the post bars, thus facilitating the manipulation, as the sheets may be handled as a unit in placing in or removing from the holders, the post bars being removed from the sheet body after it has been placed in the holder.

To facilitate this the side members of the holders are provided with slots 19 at their inner edges through the bottom of which the post bars may be removed.

15 To facilitate placing and removal of the sheet body and the placing and removal of the bottom post bar, I provide the side and end members of the holders with hand holes 20 opening to the slots 19. The holder 13 is provided with guides 21 while the holder 14 is provided with corresponding guides 22, the guides 22 extending below the holder 14.

These guides are adapted to engage the notches of the sheets and post bars and facilitate the alining of the sheets as they are transferred from one holder to the other, and also facilitate the re-engagement of the posts with the sheets, the post bars being guided by the guides both from above and below the sheet body. After the bars have been re-engaged with the sheet body, the same may be handled as a unit and replaced in the binder, or other suitable storage receptacle as a unit.

35 I preferably employ the binder as illustrated as this is very convenient for handling for reference or for filing in a vault.

40 My improved loose sheet device is very efficient in the handling of sheets, enabling the very rapid manipulation thereof with a minimum of wear and tear upon the sheets and also with a minimum of handling. For instance, when it is desired to remove a sheet at any point within the sheet body, the sheets 45 may be placed within the holder and the sheets above the desired sheet all removed as a unit with the top post bar, the sheets which remain in the holder being freed for manipulation by the removal of the bottom post bar.

50 I have illustrated and described my improvements in an embodiment which I have found very practical. I have not attempted to illustrate or describe other forms of binders or filing receptacles which I contemplate as I believe the disclosure made will enable those skilled in the art to embody or adapt my improvements as may be desired.

Having thus described my invention what 55 I claim as new and wish to secure by Letters Patent is:

60 1. The combination with sheets having notches in their binding edges and holes adjacent their binding edges, of independent post bars provided with sheet binding posts

and having notches alined with the notches of said sheets, a sheet support comprising a pair of holders having side and end members disposed so that the sheets may be arranged on the side members with their binding edges abutting the end members, the side and end members of one holder being disposed at right angles to each other and the side and end members of the other holder being arranged at acute angles to each other, 75 the side members having slots at their inner ends through which a post bar may be inserted or removed from below the holder, said side and end members having hand hold recesses in their inner edges opening to 80 said slots facilitating the manipulation of the post bars and of the sheet body, and guide members disposed on said end members to coact with the notches of said sheets and post bars, the guides on the end member disposed at right angles to its coacting side member being extended below the side member facilitating the guiding of the post bar to the sheet body.

2. The combination with sheets having notches in their binding edges and holes adjacent their binding edges, of independent post bars provided with sheet binding posts and having notches alined with the notches of said sheets, a sheet support comprising a pair of holders having side and end members disposed so that the sheets may be arranged on the side members with their binding edges abutting the end members, the side and end members of one holder being disposed at right angles to each other and the side and end members of the other holder being arranged at acute angles to each other, the side members having slots at their inner ends through which a post bar may be inserted or removed from below the holder, said side and end members having hand hold recesses in their inner edges opening to 95 said slots facilitating the manipulation of the post bars and of the sheet body, and guide members disposed on said end members to coact with the notches of said sheets and post bars.

3. The combination with sheets having notches in their binding edges and holes adjacent their binding edges, of independent post bars provided with sheet binding posts and having notches alined with the notches of said sheets, a sheet support comprising a pair of holders having side and end members disposed so that the sheets may be arranged on the side members with their binding edges abutting the end members, the side and end members of one holder being disposed at right angles to each other and the side and end members of the other holder being arranged at acute angles to each other, the side members having openings at their inner ends through which a post bar may be inserted or removed from below the 120

holder, and guide members disposed on said end members to coact with the notches of said sheets and post bars, the guides on the end member disposed at right angles to its 5 coacting side member being extended below the side member facilitating the guiding of the post bar to the sheet body.

4. The combination with sheets having notches in their binding edges and holes 10 adjacent their binding edges, of independent post bars provided with sheet binding posts, a sheet support comprising a pair of holders having side and end members disposed so that the sheets may be arranged on the side 15 members with their binding edges abutting the end members, the side members having slots at their inner ends through which a post bar may be inserted or removed from below the the holder, said side and end members 20 having hand hold recesses opening to said slots facilitating the manipulation of the post bars and of the sheet body, and guide members disposed on said end members to coact with the notches of said sheets 25 and post bars, the guide on one holder being extended below the holder side member facilitating the guiding of the post bar to the sheet body.

5. The combination with sheets having 30 notches in their binding edges and holes adjacent their binding edges, of independent post bars provided with sheet binding posts, a sheet support comprising a pair of holders having side and end members disposed so 35 that the sheets may be arranged on the side members with their binding edges abutting the end members, the side members having openings at their inner ends through which a post bar may be inserted or removed from 40 below the holder, and guide members disposed on said end members to coact with the notches of said sheets and post bars, the guide on one holder being extended below the holder side member facilitating the guiding 45 of the post bar to the sheet body.

6. The combination with sheets having notches in their binding edges and holes adjacent their binding edges, of independent post bars provided with sheet binding posts, a sheet support comprising a pair of holders having side and end members disposed so 50 that the sheets may be arranged on the side members with their binding edges abutting the end members, the side members having substantially continuous surfaces with slots 55 at their inner ends through which a post bar may be inserted or removed from below the holder, said side and end members having hand hold recesses opening to said slots facilitating the manipulation of the post bars 60 and of the sheet body, and guide members disposed on said end members to coact with the notches of said sheets and post bars.

7. The combination with sheets having 65 notches in their binding edges and holes ad-

jacent their binding edges, of a binder comprising binder members having sockets therein, post bars provided with posts disposed in alinement to coact with the holes of said sheets whereby the sheet body may 70 be handled as a unit, said post bars having notches alined with the notches of said sheets and pins adapted to coact with said sockets of said binder members, a sheet support comprising a pair of holders having 75 side and end members disposed so that the sheets may be arranged on the side members with their binding edges abutting the end members, the side members having openings at their inner ends through which a post 80 bar may be inserted or removed from below the holders, and guides disposed on said end members to coact with the notches of said sheets and post bars, the guide on one end member being extended below the side 85 member facilitating the guiding of the post bar to the sheet body.

8. The combination with sheets having notches in their binding edges and holes adjacent their binding edges, of a binder comprising binder members having sockets therein, post bars provided with posts disposed in alinement to coact with the holes of said sheets whereby the sheet body may 90 be handled as a unit, said post bars having notches alined with the notches of said sheets and pins adapted to coact with said sockets of said binder members, a sheet holder having side and end members disposed so that the sheets may be arranged 95 on the side member with their binding edges abutting the end member, the side member having opening at its inner end through which a post bar may be inserted or removed from below the holder, and a guide disposed on said end member to coact with the notches of said sheets and post bars, the guide being extended below the side members facilitating the guiding of the post 100 bar to the sheet body.

9. The combination with sheets having notches in their binding edges and holes adjacent their binding edges, of a binder, post bars removably associated with said binder and provided with sheet engaging posts and with notches alined with the notches of said sheets, and a sheet support comprising a pair of sheet holders having side and end members disposed so that the sheets may be arranged on the side members with their edges abutting the end members, the side members having openings at their inner ends through which a post bar may be inserted or removed, the end members having guides thereon coacting with the notches of the 115 sheets and post bars, the guide of one of said end members projecting below the side member to facilitate the guiding of the post bar 120 into engagement with the sheet body.

10. The combination with sheets having 130

notches in their binding edges and holes adjacent their binding edges, of a binder, post bars removably associated with said binder and provided with sheet engaging posts and 5 with notches alined with the notches of said sheets, and a sheet holder having side and end members disposed so that the sheets may be arranged on the side member with their edges abutting the end member, the side 10 member having an opening at its inner end through which a post bar may be inserted or removed, the end member having a guide thereon coacting with the notches of the sheets and post bars, the guide projecting 15 below the side member to facilitate the guiding of the post bar into engagement with the sheet body.

11. The combination with sheets having notches in their binding edges and holes adjacent their binding edges, of independently removable post bars provided with sheet engaging post and with notches alined with the notches of said sheets, and a sheet support comprising a pair of sheet holders having side and end members disposed so that the sheets may be arranged on the side members with their edges abutting the end members, the side members having openings at 20 their inner ends through which post bars 25 may be inserted or removed, the end members having guides thereon coacting with the notches of the sheets and post bars, the guides of one of said end members projecting below the side member to facilitate the 30 guiding of the post bar into engagement with the sheet body.

12. The combination with sheets having notches in their binding edges and holes adjacent their binding edges, of independently removable post bars provided with sheet engaging posts and with notches alined with the notches of said sheets, and a sheet support comprising a pair of sheet holders having side and end members disposed so that the sheets may be arranged on the side members with their edges abutting the end members, the side members having openings at 40 their inner ends through which post bars 45 may be inserted or removed, the end members having guides thereon coacting with the notches of the sheets and post bars, the guides of one of said end members projecting below the side member to facilitate the 50 guiding of the post bar into engagement with the sheet body.

13. The combination with sheets having alined holes therein, of a binding means for said sheets comprising removable post bars provided with posts adapted to be engaged 55 with the holes of said sheets, and a sheet

holder having side and end members disposed so that the sheets may be arranged on the side member with their binding edges abutting the end member, the side member having an opening at its inner end through 65 which a post bar may be inserted or removed, the end member being provided with a sheet and post bar guide projecting below the side member to facilitate the guiding of the post bar to the sheet body. 70

14. The combination with sheets having alined guiding notches at their inner ends, of a binding means for said sheets comprising a pair of independently removable binding members having guiding notches alined with the guiding notches of said sheets, and a sheet holder adapted to receive the sheet body as a unit while engaged by the binding members, said holder having a guide adapted to coact with the notches of said sheets 80 and binding members and having openings therein permitting the removal of both binding members from below the sheet body while supported in said holder, said guide member extending above and below the sheet 85 body to facilitate the adjusting of the binding members to the sheets while supported by the holder.

15. The combination with sheets having alined guiding notches at their inner ends, of a binding means for said sheets comprising a pair of independently removable binding members having guiding notches alined with the guiding notches of said sheets, and a sheet holder adapted to receive the sheet body as a unit while engaged by the binding members, said holder having a guide adapted to coact with the notches of said sheets and binding members and having openings therein permitting the removal of both binding members from below the sheet body while supported in said holder, said guide member extending below the sheet body to facilitate the adjusting of a binding member to the sheets while supported by the holder. 100 105

16. The combination with sheets, of binding means therefor comprising independently removable post bars provided with sheet-engaging posts, a sheet holder adapted to receive the sheet body and post bars as a unit 110 and having an opening in the bottom thereof through which the bottom post bar may be removed, said sheet holder being provided with a sheet and binding member guide extending below the sheet holder to facilitate 115 the engagement of the bottom post bar with the sheets.

In witness whereof I have hereunto set my hand.

GEORGE P. WIGGINTON.
